SWITCH HANDLE

John Franklin Farr, Anderson, S. C.

Application October 14, 1953, Serial No. 27,176

Term of patent 14 years

(Cl. D26—13)

To all whom it may concern:

Be it known that I, John Franklin Farr, have invented a new, original, and ornamental Design for a Switch Handle, of which the following is a specification, reference being had to the accompanying drawing, forming a part hereof.

Fig. 1 is a front elevation of the switch handle according to my invention,

Fig. 2 is a side elevation with the pattern of the features omitted for convenience of illustration,

Fig. 3 is a cross sectional view taken substantially along the line 3—3 in Fig. 1,

Fig. 4 is a rear elevation of the switch handle according to my invention.

I claim:

The ornamental design for a switch handle, substantially as shown.
